TYPEWRITING MACHINE

Walter T. Sagner, Wethersfield, Conn., assignor
to Underwood Elliott Fisher Company, New
York, N. Y., a corporation of Delaware

Application January 21, 1937, Serial No. 121,457

14 Claims. (Cl. 197—126)

This invention relates to carriage extension supporting means for typewriting machines, and is illustrated in connection with a bookkeeping machine of the Underwood type. Certain features of the invention are applicable to continuous billing machines in general in which printed forms are repeated along each ply of a multiple-ply web, to be torn off one by one when typed, the web being usually of the fan-fold type.

5 The rear frame extension of the usual continuous billing machine for supporting the carriage extension adds considerably to the bulk of the machine, making it of an inconvenient shape to store or ship.

10 15 A feature of my invention is the provision of a rearwardly extending support for the carriage extension, pivoted at its lower end to the computing part of the machine, and capable of being folded against the machine to effect a considerable saving of space for packing, shipping or storing.

20 25 I have illustrated a bookkeeping machine with a rear carriage extension of a unitary construction, which may be used on a stand or ordinary desk. Due to its size there is considerable risk that the carriage extension may be damaged due to falling or collision. With a cast support there may be breakage. I overcome this by providing a tubular support of light weight having great 30 strength and resiliency to withstand shock, and means are provided for realignment.

35 40 Another object is the provision of an adjustable rear carriage support or truss-structure that combines light weight with great strength, while retaining the resiliency desirable in tabulating mechanism.

45 50 It has been found that the momentum of the carriage extension or table, in tabulating or carriage-return operations is apt to cause a twisting of the carriage which is sufficient to cause the denominator selector to engage the wrong jack. This occurs even when the tabulating and escape- 55 ment mechanism function properly and causes incorrect results to be exhibited. It may also cause the ripping or tearing of the carbon paper or the thin tissue of the fan-fold web material.

An object of this invention is to eliminate this objectionable condition by improved rear carriage support construction and the provision of plates 50 on the rear carriage extension for engaging the rear guide rail of the support.

55 In the rear carriage support of my invention I provide two rearwardly extending tubular metallic members, pivotally connected to a trans- verse strap in the lower part of the machine

frame, and spaced apart slightly less than the width of the frame. At the upper and rearward ends the two tubular members are riveted to an angle piece extending across the width of the machine, so that the strap, tubular members, and angle piece form a rectangle. This rectangular support is held in proper position by means of two adjustable tie rods rotatably connected to lugs on the ends of the angle piece and to the upper sides of the machine frame so that the tie rods and tubular members form an acute angle. The angle-piece is arranged to carry a guide rail to support the rear carriage, and this guide rail is provided with slotted portions to adjust it so that it may be made horizontally parallel to the carriage guide-rail.

5 10 15 The above design provides a light and very strong construction to support the weight of the rear carriage. To stiffen and conduct to lateral strength, a diagonal tubular member is welded from the top portion of one tubular member to the bottom portion of the opposite tubular member, so that the tubular member and the diagonal member form two legs of a shear, whose base is the strap in the machine frame. In order 20 to secure the greatest advantage of this construction, the included angle between the shear legs is made as great as possible, and for added strength and ease of assembly the diagonal member is welded to the opposite tubular member.

25 30 35 A similar diagonal member is welded in the same manner to the opposite tubular member, so that another shear is formed, the two shears having their outer shear legs parallel and their inner shear legs crossing, forming a composite shear. The two crossing legs may be formed so as to pass each other without touching, so that two separate and independent shears are formed having their tops tied together by means of the angle piece holding the rear guide-rail. Due to 40 this double-shear construction, the support is incapable of lateral displacement in either direction.

45 50 55 To align the rear guide-rail with the carriage-rail in a vertical plane, adjustment is provided at the lower ends of the shear legs, which are pivotally secured to studs threadably engaged in the transverse strap of the lower machine frame. Rotation of these studs shifts the position of the tubular members and swings the guide-rail in an arc whose center is the pivot of the forward end of the rod. With the rear-rail thus aligned in a vertical plane, it is easily shifted in a horizontal plane by means of the slotted rail portions fastened to the angle piece.

Other features and advantages will hereinafter appear.

In the accompanying drawings,

Figure 1 is a sectional side elevation of a portion of a bookkeeping machine having the present invention applied thereto.

Figure 2 is a partial side view showing the rear carriage support folded for shipping.

Figure 3 is a view taken along the lines 3—3 of Figure 1, showing the construction of the rear carriage support and the carriage-swing resisting plates; and

Figure 4 is a plan view of the rear carriage support.

Referring now to Figure 1, a typewriter 11, having a frame 12, overlies a computer 13, which is controlled by the numeral keys of the typewriter.

The typewriter 11 comprises a platen 14 mounted on a platen-axle 15, which is rotatably supported in a travelling carriage 16. The carriage 16 is supported at its rear by a guide-rail 17 fixed on the typewriter-frame 11. The usual letter-feed mechanism 51 and escapement 52 are provided. The carriage 16 is provided at its ends with brackets 18 extending rearwardly, in which are mounted a bar 19 and a rod 20, along which selectors 53 may be moved. Tabulating means with register and denominational selecting means are provided as indicated generally at 21, and described in detail in the co-pending application No. 72,348, of H. L. Pitman, filed April 2, 1936. The brackets 18 also extend upwardly, and are connected together by a rod 55 on which are slidably positioned fingers 56 for guiding the web 57 and carbon sheets 58.

At the rear of the machine, provision is made for a carbon-carriage 22, mounted for movement forward and from the platen, upon a rear carriage extension or table 23, comprising a front member 24, secured by screws 49 to brackets 18, a rear member 25, and a plurality of connecting members 26, the two outermost ones having on their upper side rails 27, with each one of which co-operate grooved rolls 28 mounted on the base-plate 29 of the carbon-carriage 22. To support and guide the rear carriage extension at its rear end, provision is made of a guide-rail 30, mounted on an angle 31 and extending substantially parallel to the guide-rail 17. The two outermost members 26 have an angle plate 32 attached in a downwardly-extending position, and each plate 32 carries a roller 33 which rides upon the rail 30 and a hook guide 34 which partially embraces the guide-rail 30. To prevent excessive swinging movement of the carriage, at the conclusion of a tabulating or carriage-return operation, the plates 32 are provided with lateral extensions 35, to lie to the rear of the rail. These extensions are positioned to engage the rail 30 when the carriage has been swung only a slight amount, and in co-operation with the hook guides 34 to limit the swinging movement of the carriage and the carriage extension, the plate at one side of the carriage extension and the hook guide 34 at the opposite side thereof having a tendency to bind the guide rail 30 between them when the carriage is swung.

The angle 31 upon which the guide rail 30 is adjustably mounted by means of screws 36, is secured to tubular supports 37 by means of rivets 59. These supports extend downwardly and forwardly, and are pivotally connected by screws 38 to studs 39, adjustably mounted to a strap 40, in the computing section 13 of the machine.

The tubular supports 37 are joined together

and braced by means of tubular connectors 41 in the form of shears. At the crossover point, the connectors are formed so as to pass each other without touching. This construction has been found to impart the proper degree of resiliency to deaden and absorb the shock occasioned by the sudden stopping of the rear carriage extension, and still have the necessary strength to prevent distortion.

The angle 31 has forward extending lugs 42 at each end, to which tie-rods 43 are connected by means of a screw 44. The forward ends of the tie-rods 43 are secured to the frame 12 of the typewriter 11 by means of screws 45 and studs 50, and provision is made to adjust their lengths by means of a threaded portion 46 and lock-nut 47.

The tie-rods 43 are so positioned as to afford easy access to the tabulator section 21 for the purpose of setting the stops.

To adjust the rear-guide rail 30 so that it is parallel with the carriage-guide rail 17, screws 38 are removed and studs 39 rotated until the rear-guide rail 30 is parallel with the carriage-guide rail 17, in a vertical plane. To adjust in a horizontal plane, screws 36 are loosened, while in extreme cases, screws 45 are removed and tie-rods 43 rotated to a proper length.

To aid in letter-feeding, it is desirable that the guide-rails slope somewhat to the left-hand side of the machine. To accomplish this, washers 48 are inserted between the foot and the base of the computing machine on the right-hand side.

Figure 2 shows a machine packed for shipment in a box 54. Screws 49 are removed and the table 23 is removed from rear-guide rail 30. Screws 45 are then removed from studs 50, and the supports 37 and tie-rods 43 may be folded up close to the machine.

Variations may be resorted to within the scope of the invention, and portions of the improvements may be used without others.

Having thus described my invention, I claim:

1. In a typewriting machine having a base and provided with a paper carriage having a rearward extension, the combination of a rear track upon which said extension runs, and a support for said track, including two rearwardly and upwardly extending tubular members, a transverse strap to which said members are connected at their lower ends, said strap being secured to said base, said tubular members at their upper ends being fastened to a transverse tie-plate, and brace-members extending from each tubular member for anchorage adjacent said tie-plate, said tie-plate, strap and tubular members forming a rigid unitary frame.

2. In a typewriting machine having a base and provided with a paper carriage having a rearward extension, the combination of a rear track upon which said extension runs, a support for said track, including two rearwardly and upwardly extending tubular members, a transverse strap to which said members are connected at their lower ends, said strap being secured to said base, said tubular members at their upper ends being fastened to a transverse tie-plate, said tie-plate, strap and tubular members forming a rigid broad frame, and two adjustable tie-rods connected at their rear ends to said tie-plate, and at their forward ends to the upper portion of the typewriter framing; said rail being mounted upon said tie-plate.

3. In a typewriting machine having a base and provided with a paper carriage having a rearward extension, the combination of a rear track

- upon which said extension runs, a support for said track, including two rearwardly and upwardly extending tubular members, a transverse strap to which said members are connected at their lower ends, said strap being secured to said base, said tubular members at their upper ends being fastened to a transverse tie-plate, said tie-plate, strap and tubular members forming a rigid broad frame, and two adjustable tie-rods connected at their rear ends to said tie-plate, and at their forward ends to the upper portion of the typewriter framing; said rail being mounted upon said tie-plate, and said guide-rail provided with means whereby it may be adjusted horizontally into parallelism with the main guide-rail of said carriage.

4. In a typewriting machine having a carriage and a rearwardly extending frame, the combination with a rear rail upon which said extension runs, of a support for said rail secured at its lower end at the base of the typewriting machine and extending upwardly and rearwardly, and including a shear structure having members converging from said base to said rail member, to support the same.

5. In a typewriting machine having a carriage and a rearwardly extending frame, the combination with a rear rail upon which said extension runs, of a support for said rail secured at its lower end at the base of the typewriting machine and extending upwardly and rearwardly, and including a pair of shear supports each having an apex, the apex of one shear supporting said rail at one end, and the apex of the other shear supporting said rail at the other end, and means extending forwardly from said apexes to connect them with the machine framing.

6. In a typewriting machine having a carriage and a rearwardly extending frame, the combination with a rear rail upon which said extension runs, of a support for said rail secured at its lower end at the base of the typewriting machine and extending upwardly and rearwardly, and including a shear structure having members converging from said base to said rail member, to support the same, said shear structure at its lower end being adjustable relatively to the base of the typewriter.

7. In a typewriting machine having a carriage and a rearwardly extending frame, the combination with a rear rail upon which said extension runs, of a support for said rail secured at its lower end at the base of the typewriting machine and extending upwardly and rearwardly, and including a pair of shear supports each having an apex, the apex of one shear supporting said rail at one end, and the apex of the other shear supporting said rail at the other end, and means extending forwardly from said apexes to connect them with the machine framing, each of said shears including a diagonal member welded to the co-operative tubular member at the apex of the shear.

8. In a typewriting machine having a carriage and a rearwardly extending frame, the combination with a rear rail upon which said extension runs, of a support for said rail secured at its lower end at the base of the typewriting machine and extending upwardly and rearwardly, and including a pair of shear supports each having an apex, the apex of one shear supporting said rail at one end, and the apex of the other shear supporting said rail at the other end, and means extending forwardly from said apexes to connect them with the machine framing, the two shears having their outer shear legs parallel, and their inner shear legs crossing, to form a composite shear.

9. In a typewriting machine having a carriage and a rearwardly extending frame, the combination with a rear rail upon which said extension runs, of a support for said rail secured at its lower end at the base of the typewriting machine and extending upwardly and rearwardly, and including a pair of shear supports each having an apex, the apex of one shear supporting said rail at one end, and the apex of the other shear supporting said rail at the other end, and means extending forwardly from said apexes to connect them with the machine framing, the two shears having their outer shear legs parallel, and their inner shear legs crossing, to form a composite shear, said crossing shear legs being without contact, and the tops of the shears being tied together.

10. In a typewriting machine having a carriage and a rearwardly extending frame, the combination with a rear rail upon which said extension runs, of a support for said rail secured at its lower end at the base of the typewriting machine and extending upwardly and rearwardly, and including a pair of shear supports each having an apex, the apex of one shear supporting said rail at one end, and the apex of the other shear supporting said rail at the other end, and means extending forwardly from said apexes to connect them with the machine framing, the two shears having their outer shear legs parallel, and their inner shear legs crossing, to form a composite shear, said crossing shear legs being without contact, and the tops of the shears being tied together.

11. In a typewriting machine having a carriage and a rearwardly extending frame, the combination with a rear rail upon which said extension runs, of a support for said rail secured at its lower end at the base of the typewriting machine and extending upwardly and rearwardly, and including a pair of shear supports each having an apex, the apex of one shear supporting said rail at one end, and the apex of the other shear supporting said rail at the other end, and means extending forwardly from said apexes to connect them with the machine framing, the two shears having their outer shear legs parallel, and their inner shear legs crossing, to form a composite shear, said crossing shear legs being without contact, and the tops of the shears being tied together by means of the angle piece which holds the rear guide-rail of the carriage extension, the composite shear support being incapable of lateral displacement in either direction.

12. In a typewriting machine having a carriage and a rearwardly extending frame, the combination with a rear rail upon which said extension runs, of a support for said rail secured at its lower end at the base of the typewriting machine and extending upwardly and rearwardly, and including a pair of shear supports each having an apex, the apex of one shear supporting said rail at one end, and the apex of the other shear supporting said rail at the other end, and means extending forwardly from said apexes to connect them with the machine framing, the lower ends of the shear legs being pivotally secured to studs which are threaded into a transverse strap on the base of the typewriter.

13. In a typewriting machine having a carriage and a rearwardly extending frame, the combination with a rear rail upon which said extension runs, of a support for said rail secured at its lower end at the base of the typewriting machine and extending upwardly and rearwardly, and including a pair of shear supports each having an apex, the apex of one shear supporting said rail at one end, and the apex of the other shear supporting said rail at the other end, and means extending forwardly from said apexes to a pivotal connection with the machine framing, the lower ends of the shear legs being pivotally secured to studs which are threaded into a transverse strap on the base of the typewriter, rotation of the studs being effective to shift the position of the shear supports, and swing the guide-rail in an arc whose center is the pivot of the forward end of said forwardly extending means, said rear rail being thereby aligned to a vertical position, and being shiftable in a horizontal plane by means of slotted connections to said apexes.

13. In a machine of the character indicated, having a traveling carriage, in combination, a table extending from said carriage, a rail upon which said table travels, and having a support on the machine, said rail support comprising a frame including spaced side members affixed to said rail and flexibly joined to the machine, diagonal members fixed to opposed ends of said side members and clearing each other at their intersections to afford flexibility in the plane of said frame, and adjustable rods extending between said machine and the rail attachment ends of said side members, whereby to permit alignment of

said rail relatively to the travel of said carriage.

14. In a typewriting machine having a frame and a carriage on said frame having a rearward extension; the combination with a rear track upon which said extension runs, of a truss structure supporting said track and comprising two divisions having pivotal joints to the frame and converging triangularly to and connected by a third pivotal joint behind said frame, and means readily adjustable for effecting adjustment of the relative locations of said pivotal joints, whereby to adjust said track.

WALTER T. SAGNER.
